UNITED STATES PATENT OFFICE

136,981

DESIGN FOR A MINING MACHINE

Clyde P. Baldwin, Claremont, N. H., and Harry H. Vanderzee, Michigan City, Ind., assignors to Sullivan Machinery Company, a corporation of Massachusetts

Application June 21, 1943, Serial No. 110,501

Term of patent 14 years

To all whom it may concern:

Be it known that we, Clyde P. Baldwin, a citizen of the United States, residing at Claremont, in the county of Sullivan and State of New Hampshire, and Harry H. Vanderzee, a citizen of the United States, residing at Michigan City, in the county of Laporte and State of Indiana, have jointly invented a new, original, and ornamental Design for a Mining Machine, of which the following is a specification, reference being had to the accompanying drawings, forming a part hereof, whereof

Fig. 1 is a top plan view of a mining machine, showing our new design.

Fig. 2 is a perspective view of the front and one side thereof, with parts adjusted into a different position and with the cuttings deflecting shield attached.

Fig. 3 is a perspective view of the front and one side thereof, similar to Fig. 2, with parts adjusted into a different position and with the cuttings deflecting shield attached.

Fig. 4, is a side perspective view thereof, with the parts adjusted as shown in Fig. 1.

Fig. 5 is a front end perspective view thereof with the parts adjusted as shown in Figs. 1 and 4.

Fig. 6 is a perspective view of the rear, top, and one side thereof, with the parts adjusted into a still different position.

We claim:

The ornamental design for a mining machine, as shown.

CLYDE P. BALDWIN.
HARRY H. VANDERZEE.
